UNITED STATES PATENT OFFICE.

HOWARD L. INGERSOLL, OF WHITE PLAINS, NEW YORK.

CAR-END CONSTRUCTION.

Application filed June 7, 1923. Serial No. 643,935.

Railroad freight cars designed and placed in service a decade or more ago are failing to meet present day conditions brought about by the longer trains, heavier locomotives and the classification hump yard. This is particularly true of the end constructions which are being knocked out or broken by the shifting of the lading as the end has been weakened by the torsional and weaving movements of the car in service, which service conditions it was not designed to meet. This is especially true of box and other house cars.

The end constructions fail in numerous ways, the most frequent of which is by the end or corner post breaking or becoming detached from their moorings at top or bottom. The end sills decay and fail to perform their function of supporting the draft 15 sills from drooping. The end sheathing decays where it is nailed to the end sill so that it not only fails to hold the grain within the car but also does not perform its function as a gusset or bracing to resist the lateral weaving of the car body.

It is expensive to replace an end of a car on account of the cost of material and labor, as well as the time the car is out of service and, therefore, not producing revenue. Investigation shows that the ends of a box car 20 must be replaced or repaired two or three times a year on an average. All steel car ends are in general use and are easily applied to new equipment as the design can be arranged to accommodate them, but it is expensive in time and material to apply such all steel car ends for repairs, because the old wooden end walls of the car must be removed before the steel end is applied. The 25 old end is scrapped and wasted.

One of the objects of this invention is to provide means for reinforcing and strengthening the vulnerable parts of the old end wall of the old car without necessarily removing or replacing the old members thereof, even though such frame members are broken.

The invention resides in providing a corrugated or otherwise reinforced plate which can be applied on the exterior of the old wall and is secured on its vertical edges to members which overlap the old corner post of the car and is secured thereto so as to reinforce this post. The lower flat margin 30 of the corrugated plate overlies the outer face of the end sill and is secured thereto

by truss rods, bolts or other means so that it reinforces the end sill in a vertical direction. The corrugated plate is also secured to the end post so that these members are 35 reinforced. The corrugated plate also reinforces the end diagonal braces.

Another object is to reinforce the end sill of the car without removing or replacing it.

If the bottom end of the sheathing boards 40 is rotted to such an extent that it cannot be renailed it may be advisable to remove the lower portion of these boards and place the reinforcing corrugated plate directly 45 against the end framing of the car and allow the end sheathing boards to overlap the top 50 of the plate for weatherproofing. Another object is to make the car grain proof without the necessity of removing and replacing the end sheathing.

Over three-quarters of the damages to car 55 end walls occur within 30" of the floor. Another object is to distribute the thrust on the lower part of the end wall to the 60 side wall of the car.

It is preferably not to flange the reinforcing plate along its vertical edges, but to secure it to a separate angle so that the plate can be applied to any width of car by 65 adjusting the position of the angle to suit. By this means the corrugated flat plate is 70 interchangeable with other cars. If a car is destroyed or retired the corrugated plate 75 can be salvaged and used on other equipment.

Another object of the invention is to provide means for resisting the lateral weaving 80 of the car which is accomplished by attaching a reinforcing corrugated plate to the end frame members of the car, either directly or indirectly.

In the drawings:

Fig. 1 is an end elevation of a railway 85 box car showing the device applied thereon.

Fig. 2 is a section along line 2—2 of Fig. 1.

Fig. 3 is a fragmentary side elevation of 90 Fig. 1.

In the drawings 1 is the usual end sill; 2 the end plate; 3 the corner post; 4 the end post; 5 the end diagonal braces; 6 the lower 95 end girth; 7 the upper end girth; 8 the lower side girth; 9 the upper side girth; 10 the side diagonal brace; 11 the side plate; 12 the side 100 sill; 13 the end lining and 14 the end sheathing. The reinforcing plate 22 has integral corrugations 15 or reinforcing ribs formed 105 therein so as to reinforce the entire area between the adjusting angles on the opposite 110

sides of the car. The adjusting angles 16 are secured to the reinforcing plate 22 and extend vertically from a point adjacent the side sill 12 to the lower girths 8 and may be 5 extended vertically as high as necessary to sufficiently reinforce the corner post 3. The adjusting angles 16 are secured to the side sill 12 and lower side girths 8 and possibly to the upper side girths 9. A reinforcing 10 connecting band or angle 17 extends along the top edge of the reinforcing plate 22 and extends to lap the side wall of the car and is secured to the side girths and preferably also to the side diagonal brace 18. This 15 member may be of any desired cross section.

I claim:

1. An end wall for a railway car comprising an end sill, corner posts, end posts, supplemental posts, and a wooden interior lining 20 in combination with an outside sheathing, the upper part of said sheathing consisting solely of a plurality of wooden boards

and the lower part of said sheathing consisting solely of a metallic plate reinforced with integral corrugations which terminate within the plate, said supplemental posts reinforcing the corner post and providing means for securing the plate thereto. 25

2. An end wall for a railway car comprising an end sill, corner posts, end posts, supplemental posts, an end girth, and a wooden interior lining in combination with an outside sheathing, the upper part of said sheathing consisting solely of a plurality of wooden boards and the lower part of said 30 sheathing consisting solely of a metallic plate reinforced with integral corrugations which terminate within the plate, said supplemental posts reinforcing the corner post and providing means for securing the plate 35 thereto, said end girth secured to the upper edge of the plate and to both supplemental posts.

HOWARD L. INGERSOLL.
